UNITED STATES PATENT OFFICE

2,273,243

FUEL INJECTING DEVICE

Augustus V. Zanetti, Clifton, N. J.

Application December 5, 1938, Serial No. 244,092

1 Claim. (Cl. 299—107.6)

My invention relates to improvements in fuel injection devices for use with internal combustion engines wherein liquid fuel is delivered directly into the cylinder during the compression stroke.

One of the principal objects of my invention is to provide a fuel injector nozzle which is simple in construction, durable in use, efficient in operation and economical in manufacture.

Another object of my invention is to provide a fuel injector nozzle of the character described equipped with a nozzle tip having fuel orifices so arranged and constructed as to maximize the atomization of the fuel oil so as to mix with a maximum amount of air upon introduction into the compression chamber of the engine.

An important object of my invention is to provide a device of the character described wherein the fuel orifices are so constructed as to simplify the manufacturing of the nozzle tips by eliminating the tedious and difficult operations of drilling a large number of relatively small holes in the nozzle tip as has heretofore been the practice and which, in some instances, said holes are of diameters of .007" and with tolerances of .0002".

Other objects and advantages will be apparent from the following description, appended claim and annexed drawing.

Referring to the drawing wherein like reference characters designate like parts throughout the several views:

Figure 1 is a vertical sectional view, partly in elevation, of a nozzle constructed in accordance with my invention.

Figure 2 is a plan view of the nozzle tip.

Figure 3 is a sectional view taken on the line 3—3 of Figure 1.

In practicing my invention, I provide a fuel injector nozzle 5 comprising a nozzle retaining sleeve 6 fitted within a wall 7 of a cylinder head. The lower end of the nozzle sleeve is reduced on the periphery thereof to form a shoulder for engagement with a gasket 8 fitted on a similar shaped shoulder in the opening of the cylinder wall through which the sleeve extends. The upper end of the sleeve 6 has threaded therein the lower threaded end of an injector body 9 and which is fashioned with a longitudinally extending passage 9a connected by means of a pipe 10 to a pump for feeding fuel oil into the device.

Mounted in the sleeve 6 subjacent the lower end of the body is an injector valve cylinder 10a and which is formed with a lengthwise extending fuel passage 11, the upper end of which communicates with the passage 9a. The lower end

5 of the passage 11 communicates with a fuel oil chamber 12 formed in said valve cylinder above the lower end thereof. The valve cylinder 10a is fashioned above the chamber 12 with a centrally disposed bore 13 in which is slidably mounted a valve stem 14. The lower end of the valve stem 14 is shouldered as at 14a and formed with a reduced shank 15 normally disposed within the chamber 12.

10 The lower end of the shank 15 is provided with an inverted frustum shaped valve member 16 seated in a similar shaped seat 17 formed in the lower end of the valve cylinder 10a. The lower end of the valve seat 17 communicates with the upper open end of a centrally disposed bore 18. The under face of the cylinder 10a has formed thereon a subjacently extending nozzle tip 19, the upper end of which is of a cylindrical shape and spaced from the adjacent wall of the sleeve. The lower end of said tip is of a frustum configuration and has formed therein a plurality of inwardly and upwardly extending fuel oil passages 20, the inner ends of which communicate with the lower end of the cul-de-sac 18. The outer end of the passage 20 communicate with a circumferentially extending groove 21 formed in the peripheral face of the lower end of the tip. The lower face of the tip is recess while the peripheral face adjacent the recess is formed with a plurality of spirally arranged discharge orifices 22. The inner ends of the orifices 22 communicate with the groove 21. The lower end of the sleeve is formed with a bore having inner and outer oppositely disposed inclined walls 23 and 24 respectively and the wall 23 coacts with the peripheral face of the frustum shaped end of said tip to direct sprays of fuel oil from the groove 21 into the cylinder through the orifices 22.

15 The outer face of the cylinder 10a is provided with a lengthwise extending slot 10b through which any leakage of oil from the tip may flow. The body 9 is provided with a passage 9b communicating with a groove 10c formed in the upper face of the cylinder and which communicates with the slot 10b for receiving said oil. The upper end of the passage 9b has connected thereto the end of a pipe through which the oil is discharged into a suitable reservoir or the like.

20 The upper end of the valve stem 14 is positioned an appreciable distance below the lower face of the body when the valve member 16 is in seated condition and said upper end of the valve stem is fashioned with a projection 14c extending through the lower end of a bore 10d formed

in the body. Slidably mounted in said bore is a spring pressed plunger 25, the lower end of which receives therein the upper end of the projection 14c. The upper end of the plunger extends through a bushing 26 threaded into the bore at the upper end of the body.

Mounted on said plunger is a spring 27, the upper end of which engages the lower end of said bushing whereby adjustment of said bushing relative to the body serves to vary the tension of the spring 27 to regulate the actuation of the valve stem 14. A lock nut 29 is secured about the upper end of said bushing and serves to lock the latter in adjusted position on the upper end of said body.

In operation, oil is introduced into the chamber 12 through the passages 9a and 11 and due to the pressure thereof serves to actuate the valve stem 14 upwardly against the tension of the spring 27 and thereby unseat the valve member 16 to permit said oil to be discharged into the cul-de-sac 18 and into the groove 21 through the passages 20. When the oil is thus discharged into the groove 21, the same is atomized into the cylinder through the medium of the spirally arranged grooves 22.

From the foregoing it will be apparent that I have provided a simple and efficient nozzle equipped with a nozzle tip for maximizing the atomization of the fuel oil whereby to effect a mixture thereof with a maximum amount of air within the cylinder.

It is obvious that the invention is not confined to the herein described use therefor as it may be utilized for any purpose to which it is adapt-

able. It is therefore to be understood that the invention is not limited to the specific construction as illustrated and described, as the same is only illustrative of the principles of operation, which are capable of extended application in advance forms, and that the invention comprehends all construction within the scope of the appended claim.

What I claim is:

10 In a nozzle of the character described, a sleeve reduced at its outer end portion to form a circular centrally disposed discharge orifice therein, the said reduced portion being shaped to form an inner frusto-conical section providing a
15 seat having an increasing taper inward from the orifice and an outer frusto-conical wall flaring outwardly from the orifice, a nozzle member mounted within the sleeve having a frusto-conical tip portion at one end seated on the seat portion of the sleeve, the outer end of the tip having a depression therein shaped to form a flaring circumferential wall co-extensive with the exterior flaring portion of the sleeve, the said nozzle member having an axial feed bore terminating inwardly of the tip and communicating through a plurality of oblique ducts with a circumferential groove in the frusto-conical portion of the tip, the latter groove forming an annular chamber in conjunction with the seat and
20 communicating with a plurality of spiral shaped ducts formed through the medium of grooves in the tip, and discharging through the orifice through the flaring circumferential wall at the outer end of the tip.

25 30 AUGUSTUS V. ZANETTI.
